VULCANIZATION OF RUBBER

William E. Messer, Cheshire, Conn., assignor to
United States Rubber Products, Inc., New
York, N. Y., a corporation of Delaware

No. Drawing. Application February 16, 1935,
Serial No. 6,807

2 Claims. (Cl. 18—53)

This invention relates to the use of new and improved accelerator combinations, useful in the production of vulcanized rubber goods.

An object of this invention is to provide a new activator for organic accelerators and more particularly for thiazyl sulphide vulcanization accelerators such as the arylene thiazyl sulphides and disulphides which when used in conjunction therewith will tend to produce less scorching and better calendering as well as better ageing rubber stocks.

These activators are characterized in being broadly amino thiophenols characterized by the grouping

15

20 wherein R is hydrogen or a substituted element or group. Examples are o-amino thiophenol, o-o' diamino-diphenyl disulphide, o-o' diamino-diphenyl monosulphide, p-amino thiophenol, p-p' diamino-diphenyl monosulphide, m-amino thiophenol, m.m'-diamino-diphenyl disulphide, m.m'-diamino diphenyl monosulphide, o-p'-diamino diphenyl disulphide, o-p'-diamino diphenyl sulphide and halogen and/or alkyl nuclear-substituted derivatives thereof. The salts 25 and acyl derivatives of the amino thiophenols may also be used, as where the hydrogen of the sulphydryl group is replaced by metal or an acyl group.

30 The following example is given to illustrate preferred aspects of the invention and is not to be construed as limiting thereof. The parts given are parts by weight. T stands for tensile in pounds per square inch at break, and E stands for percent elongation at break. The stock that 35 is tested for scorching properties, and tensiles before and after ageing is a tire tread stock.

Example 1

45	Stock	Parts		50
		A	B	
Smoked sheets.....	100.00	100.00		
Carbon black.....	42.00	42.00		
Zinc oxide.....	10.00	10.00		
Pine tar.....	3.50	3.50		
Sulphur.....	3.25	3.25		
Zinc soap of cocoanut oil acids.....	4.00	4.00		
Mercaptobenzothiazole.....	1.25	.30		
o-o' diamino diphenyl disulphide.....		.90		

Scorch test (5 pounds per sq. in. steam pressure)

Cure in minutes	A		B		5
	T	E	T	E	
75.....	1665	745	1017	795	
80.....	2527	817	1692	802	
90.....	2760	782	2107	817	

10

Unaged

Cure in mins. at 30 lbs. sq. in. steam pressure	A		B		15
	T	E	T	E	
20.....	3910	703	2820	676	
30.....	3970	643	3960	703	
40.....	4100	603	4400	690	
50.....	4680	623	4530	673	20
60.....	4510	600	4610	666	

Aged 24 hrs. at 212° F.

20.....	3636	406	3780	495	25
30.....	3197	365	3815	425	
40.....	3685	365	3790	445	
50.....	3265	380	2755	360	
60.....	2780	345	3430	440	

Aged 168 hrs. in oxygen bomb (300 pounds 30
oxygen maintained at 60° C.)

20.....	1060	605	1567	567	
30.....	1895	565	1825	557	
40.....	1693	452	1737	510	
50.....	1472	452	1592	475	35
60.....	1210	385	1412	412	

It will be observed that the initial cure, as shown by the scorch test, is retarded by use of the combination in B. Also that the optimum cure is reached at about the same time as with the full amount of mercaptobenzothiazole (stock A) which shows that an economy in use of the thiazole accelerator may be obtained by the present invention and further with an improvement in ageing properties. 40

Instead of mercaptobenzothiazole, its disulphide, mercapto-benzo-thiazole-disulphide (di-benzothiazyl disulphide) may be used, as well as other well known thiazole accelerators which are 50 derivatives, substitution products or salts of mercaptobenzothiazole illustrated by dinitro phenyl ester of mercaptobenzothiazole, benzoyl benzothiazyl sulphide, etc.

The amount of activator usable may vary from 55

that specifically shown. Generally it is usable in the same proportions as prior art activators of organic accelerators. The term rubber is to be construed broadly as including caoutchouc, balata, gutta percha, rubber isomers, synthetic rubber, and is applicable to latex whether naturally occurring or artificially preferred.

5 The activators may be used with different types of stock than that illustrated, with other compounding ingredients and other proportions of ingredients. In the case of white stocks the activator is substantially non-discoloring which is another attribute of this invention.

Having thus described my invention, what I 10 claim and desire to protect by Letters Patent is:

1. A process of producing vulcanized rubber goods which comprises accelerating the vulcanization of a vulcanizable rubber stock with an arylene thiazyl sulphide accelerator and an added

amount of an activator therefor having the general formula

5

where R is H or the grouping within the parenthesis the proportion of activator being greater than the proportion of the sulphide accelerator. 10

2. A process of producing a vulcanized rubber product which comprises incorporating in rubber prior to vulcanization a vulcanizing agent, an arylene thiazyl sulphide accelerator and a substantially pure diamino-diphenyl sulphide in 15 which the proportion of the diphenyl sulphide preponderates over the proportion of the sulphide accelerator.

WILLIAM E. MESSER.
